UNITED STATES PATENT OFFICE.

AMANDUS H. CRUSE, OF NEW YORK, N. Y., ASSIGNOR TO ROBERT HOE, OF NEW YORK, N. Y.

MACHINE FOR MAKING SAWS.

SPECIFICATION forming part of Letters Patent No. 746,297, dated December 8, 1903.

Application filed September 26, 1901. Serial No. 76,591. (No model.)

To all whom it may concern:

Be it known that I, AMANDUS H. CRUSE, a citizen of the United States, residing at New York, county of Kings, and State of New York, have invented certain new and useful Improvements in Machines for Making Saws, fully described and represented in the following specification and the accompanying drawings, forming a part of the same.

This invention relates to certain improvements in machines for making saws.

In making saws which employ inserted teeth the rims of the sockets in which the teeth are inserted are beveled on both sides to provide bearings for the shanks which lock the teeth in position. In the machines heretofore usually employed for beveling the sockets the saw is clamped to a horizontal table and each of the sockets is subjected in succession to the action of a vertical cutter, which is perpendicular to the side of the saw and which produces the required bevel on one side of the rim of the socket. When the rim of each socket has been beveled on one side, the saw is turned over and the opposite side of the rim of each socket is similarly beveled. In forming these bevels the greatest accuracy is necessary, the machines usually being required to work within a thousandth part of an inch. It is frequently necessary, therefore, to subject one or more of the sockets to the action of the cutter four or five times, first on one side and then on the other, in order that the bevel may be formed with that absolute accuracy which is necessary. The operation of forming these sockets is therefore slow and is expensive.

The present invention has for its object to produce an improved machine in which the bevels on both sides of the rim of each socket may be formed simultaneously.

A further object of the invention is to produce a machine in which the bevels on both sides of the rim of the socket may be formed simultaneously and in which the position of the cutters for forming the bevels may be accurately controlled.

A further object of the invention is to produce an improved machine in which the bevels on both sides of the rim of the socket are formed simultaneously and in which cut-

ting devices which are staggered with relation to each other are employed to effect the cutting.

A further object of the invention is to produce an improved clamping device for use with machines for beveling the rims of sockets.

With these and other objects in view the invention consists in certain constructions and in certain parts, improvements, and combinations, as will be hereinafter fully described and then specifically pointed out in the claims hereunto appended.

In the accompanying drawings, which form a part of this specification, and in which like characters of reference indicate the same parts, Figure 1 is a front elevation, partly in section, of a machine embodying the invention. Fig. 2 is a sectional plan view on the line 2 2 of Fig. 1. Fig. 3 is a detail section on the line 3 3 of Fig. 1. Fig. 4 is an enlarged detail view of the clamping device. Fig. 5 is a sectional detail view illustrating the mechanism for operating the clamping device. Fig. 6 is an enlarged sectional detail showing the construction of the cutter-head and certain means for operating it. Figs. 7 and 8 are side and front elevations, respectively, of the clamping-plate employed. Fig. 9 is a detail view illustrating the beveled socket of a saw, the bevels of which the machine is designed to form.

Referring to the drawings, which illustrate one embodiment of the invention, 1 indicates the frame of the machine, which may be of any desired form of construction, and the machine employs two cutting devices, which may be widely varied in construction. As shown, these cutting devices comprise two cutter-heads 2 and 3. Each of the cutter-heads will be provided with a plurality of cutting-knives, which may be varied in number. As shown, each cutter-head is provided with four knives, the knives on the cutter-head 2 being marked 4 and the knives on the cutter-head 3 being marked 5. These cutter-heads may be driven in any suitable manner. As shown, the head 3 (see Fig. 6) is screwed into a conical socket in a spindle 6, the end of the socket being preferably strengthened by a nut 7. Similarly the cutter-head 2 is mounted on a spindle 8, the details of construction being the same as those

illustrated for the cutter-head 3. The spindle 6 has a bearing in a sleeve 9, which is suitably supported in the frame, and the spindle 8 has a bearing in a similar sleeve 10, the outer ends of these spindles being supported in brackets 11 and 12, suitably secured to the frame.

The spindles 6 and 8 may be driven in any suitable manner. As shown, the spindle 6 is provided with a bevel-gear 13, which is secured to the spindle by means of a feather, so that the spindle may have a lengthwise movement with respect to the gear. This gear 13 is suitably supported in the frame, a bushing 14 being provided for this purpose, and is driven by means of a bevel-gear 15, which is secured to a shaft 16, which is suitably supported in bearings in the frame 1. This shaft 16 is provided with a bevel-gear 17, which is in turn driven by a bevel-gear 18 on the main driving-shaft 19. The connection between the gear 18 and the shaft 19 is preferably formed by means of a clutch-collar 20, the purpose of which will be hereinafter stated.

The driving mechanism for the spindle 8 is similar to that for the spindle 6. This spindle is provided with a bevel-gear 21, which meshes with a similar gear 22, mounted on a shaft 23, which is suitably supported in the frame. This shaft 23 is provided with a bevel-gear 24, which meshes with a similar gear 25 on the main shaft 19.

The main shaft may be driven in any suitable or desired manner, but is shown as provided with a series of belt-pulleys 26, of varying diameter, in order that the speed of the machine may be increased or decreased, as desired.

Referring to Fig. 9, which is a sectional view of a part of the saw S, illustrating one of the sockets, it will be seen that the socket is provided with bevels 27 28, the machine being designed to cut these bevels. It will be seen that the bevels form an angle which is more or less acute, and it will be readily understood that the cutters usually employed in cutting the bevels will be wider than the depth of the bevels. The cutters will, therefore, project beyond the apex of the angle formed by the bevels, and in order to prevent the cutters of one cutter-head striking the cutters of the other cutter-head the cutters of each head are staggered with relation to the cutters of the other head. The positioning of the cutters so that those on one head are staggered with relation to those on the other head may be effected in any suitable manner. In the machine shown, however, the clutch 20, hereinbefore referred to, is provided for this purpose. By disconnecting this clutch it will be seen that the line of driving connections between the main shaft and the cutter-head 3 is interrupted. If now the main shaft be slightly turned, the cutter-head 3 may be given a greater or less rotation, so as to stagger its cutters with relation to those

of the cutter-head 2. After the cutters have been accurately positioned the clutch 20, which is of ordinary construction, is slipped back into position and the line of driving connections from the shaft 19 to the head 3 is re-established.

The feeding mechanism by which the cutters are advanced during the cutting operation may be of any desired construction. As shown, the sleeve 9 is provided with a rack 30, (see Fig. 6,) and the sleeve 10 is provided with a similar rack. (Not shown.) Gear-wheels 31 are provided which engage with these racks, these gear-wheels being mounted on shafts 32, which are suitably supported in the machine-frame. These shafts 32 carry worm-gears 33, which engage with worms 34 on a worm-shaft 35, the worms and the two trains of gearing being so arranged that as the shaft 35 revolves in one direction the cutters advance toward each other and the work, and as the movement of the shaft is reversed the cutters are caused to retreat from each other and the work.

In order to compensate for variations in the height of the cutters, by which is meant the distance of the edge of the cutters from the cutter-head, or for other reasons, it is desirable to provide means by which the cutters may be adjusted toward and from each other. While this adjustment of the cutters may be effected in any suitable manner, it is preferably accomplished through the feeding mechanism, and to this end in the construction shown the worm-shaft 35 is mounted in a bearing 36, which is carried on a block or plate 37. This plate 37 is secured by bolts 38 to a plate 39, which is suitably secured to the frame of the machine by bolts or in any other suitable manner. This plate 39 is provided with slots 40, (see Fig. 3 and dotted lines in Fig. 2,) through which the bolts 38 pass. When it is desired to adjust the cutters, the shaft is turned until one of the cutters is brought against the saw. The nuts on the bolts 38 are then loosened and the shaft again turned. The saw will act as a stop for the cutter which rests against it, and the worm-shaft will advance the other cutter and at the same time be moved lengthwise itself, so as to bring the cutter which it is desired to adjust up against the saw. When this has been done, the bolts are again tightened, fixing the cutters in adjusted position. The shaft may then be moved to move the cutters toward or away from the work in the ordinary manner.

The shaft 35 may be driven in any suitable manner. Preferably, however, it will be provided with means by which it may be driven by hand or by suitable mechanism which is automatically operated—that is to say, driven from a suitable source of power. In order to drive it by hand, it is provided at one end with an ordinary hand-wheel 41. To drive it automatically, it is provided with a gear-wheel 42, which is secured in position by

means of a clutch 43 or by any other suitable means. Preferably, however, these means will be such as to permit the wheel 42 to be disconnected from the shaft when desired.

5 This gear-wheel 42 is a spiral gear and is engaged by a worm 44 on a worm-shaft 45, which may be driven in any suitable manner. As shown, it is provided with pulleys 46, of varying diameter, said pulleys being driven by a 10 cross-belt 47 from a similar set of pulleys 48 on the shaft 23.

In the ordinary operation of the machine the cutters will be fed by the power-operated means described. Frequently, however, in 15 order to bring the sockets to the exact gage required it will be necessary to subject the sockets to the action of the cutters for a very short period. When such an operation as this is to be performed, and sometimes under 20 other circumstances, it will be desirable to control the feed of the cutters by means of the hand-wheel 41, before referred to.

Suitable means are preferably provided to 25 limit the depth of the cut produced by each cutter. These means may be of any suitable description, and two forms of such devices are shown, either or both of which may be relied upon. As shown, each of the sleeves 9 and 10 is provided with a collar 49, said collars serving to support adjusting-screws 50, which will strike against the frame of the machine when the cutters have reached the desired depth. When the screws strike the machine-frame, the forward feeding movement 35 of the cutters is interrupted, the belt-driving connection slipping at this time, so that no unnecessary strain is brought upon the feeding mechanism.

In addition to the stop just described each 40 of the spindles 6 and 8 is provided with a pair of hand-nuts 51, the end of the shaft being preferably reduced, as shown, and threaded. Between the inner one of these hand-nuts 51 and the frame of the machine are located 45 three collars 52, 53, and 54, the collar 53 being provided with balls, as shown, and the collar 52 bearing against the brackets in which the spindles are mounted. With this construction it will be seen that when the collars 52 strike the brackets 11 and 12 the further advance of the spindles will be interrupted and the feed operation stopped, the belt-driving mechanism slipping as before.

Any suitable means may be provided for 55 supporting the saws, so that they may be acted upon by the cutters. Inasmuch as the machine which has been selected to illustrate a concrete embodiment of the invention is designed for the purpose of cutting sockets 60 in circular saws, the support will be an axial one, so that each saw may be turned upon it to bring each socket in position to be acted upon by the cutters. In the construction shown (see Figs. 2 and 3) the machine is provided with a grooved arm 55, which operates 65 to support a stud 56, having a head which fits in the groove and which passes through

the opening in the center of the saw, the saw being held on the stud by means of a nut and washer 57 or in any other suitable manner. 70 By varying the position of the stud in the groove it will be readily perceived that saws of any desired diameter may be operated upon.

In order to prevent any swerving or springing of the cutters when in operation, guides 75 are preferably provided for each of the cutter-heads. While these guides may be of any suitable form, in the construction shown the cutter-head 2 passes through a plate or block 80 58, which is or may be provided with integral arms 59, by which it is secured to the frame. As shown, these arms are also integral with the frame, though they might be separate therefrom and secured thereto in any desired manner. Similarly, the cutter-head 3 passes 85 through a block or plate 60, whose integral arms 61 serve to secure it to the frame.

In order to firmly hold the saw in position while the cutters are operating upon it, suitable clamping devices will be provided. 90 These clamping devices may be varied widely in construction. As shown, however, there is provided a clamping-plate 62, (see Figs. 7 and 8,) said plate being provided with a recess 63, which corresponds in shape with the 95 socket in the saw to be operated upon. This plate is provided on its under side with a bearing-rib 64, which surrounds the socket. This plate 62 is located between blocks 58 and 60, before referred to, and is supported 100 in the construction shown by a pin 65, which is mounted on the block 58, and enters a socket 66 in the plate 62. In the construction shown the face of the block 58 is planed off perfectly true, and this block co-operates 105 with the plate in the clamping operation, forming the backing-up block for the plate, the saw being thus held between the plate and the block.

Any suitable means may be provided to 110 force the clamping-plate 62 against the saw. As shown, the plate is provided with headed pins 67, which are screwed into the plate and which pass through perforations in the block 60, springs 68 being provided between the 115 heads of the pins and the block, as is clearly shown in Figs. 4 and 5. Lever-blocks 69 are provided, which are fulcrumed on projections 70 on the frame and are operated by levers 71, the construction being clearly shown in Fig. 120 5. When the levers 71 are operated, it will be seen that the headed pins 67 are thrown inward and will force the rib 64 of the plate 62 firmly against the saw in proximity to the edge or rim of the socket, to be operated upon 125 by the cutters. To prevent the plate from tipping, it is provided with a support which, as shown, consists of a pair of feet 72, which rest against the saw. Adjustable means are further preferably provided to assist the support in setting the plate so that it may act 130 evenly on saws of different thickness. In the construction shown these adjustable means consist of screws 73, which pass through the

block 58 and enter recesses 74 in the plate. By providing adjustable means, such as the screws, the operation of the clamping-plate may be varied according to the thickness of 5 the saw to be operated upon.

While the construction which has been described is an effective one for carrying out the invention, it is to be understood that the invention may be embodied in other constructions which differ widely in form. It is to be further understood that certain features of the invention may be employed independently of other features, and such independent use is contemplated. The invention is not, 15 therefore, to be limited to the specific construction hereinbefore set forth.

What is claimed is—

1. In a machine for beveling sockets in saws, the combination with means for supporting the saw, of a pair of oppositely-arranged beveling-cutters, one on each side of the saw, means for driving the cutters, and means for feeding the cutters toward each other, substantially as described.

25 2. In a machine for beveling sockets in saws, the combination with means for supporting the saw, of a pair of oppositely-arranged beveling-cutters, one on each side of the saw, means for driving the cutters, means 30 for feeding the cutters toward each other, and clamping devices operating to hold that part of the saw upon which the cutters operate, substantially as described.

3. In a machine for beveling sockets in saws, the combination with means for supporting the saw, of a pair of oppositely-arranged cutter-heads, one on each side of the saw, a plurality of beveling-cutters mounted in each head, the cutters of one head being 40 staggered with relation to the cutters in the other head, means for driving the heads, means for feeding the heads toward each other, and clamping devices operating to hold that part of the saw upon which the cutters operate, substantially as described.

4. In a machine for beveling sockets in saws, the combination with an axial support for the saw, of a pair of oppositely-arranged beveling-cutters, one on each side of the saw, 50 means for driving the cutters, means for feeding the cutters toward each other, and clamping devices operating to hold that part of the saw upon which the cutters operate, substantially as described.

5. In a machine for beveling sockets in saws, the combination with an axial support for the saw, of a pair of oppositely-arranged cutter-heads, one on each side of the saw, a plurality of cutters mounted in each head, 60 the cutters of one head being staggered with relation to the cutters in the other head, means for driving the cutter-heads, means for feeding the heads toward each other, and clamping devices operating to hold that part 65 of the saw upon which the cutters operate, substantially as described.

6. In a machine for beveling sockets in saws, the combination with means for supporting the saw, of a pair of oppositely-arranged beveling-cutters, one on each side of 70 the saw, means for simultaneously driving the cutters, means for simultaneously feeding the cutters toward each other, and clamping devices operating to hold that part of the saw upon which the cutters operate, substantially as described.

7. In a machine for beveling sockets in saws, the combination with means for supporting the saw, of a pair of oppositely-arranged beveling-cutters, one on each side of 80 the saw, means for simultaneously driving the cutters, automatic means for simultaneously feeding the cutters toward each other, and clamping devices operating to hold that part of the saw upon which the cutters 85 operate, substantially as described.

8. In a machine for beveling sockets in saws, the combination with means for supporting the saw, of a pair of oppositely-arranged beveling-cutters, one on each side of 90 the saw, means for simultaneously driving the cutters, hand-operated means for simultaneously feeding the cutters toward each other, and clamping devices operating to hold that part of the saw upon which the cutters operate, 95 substantially as described.

9. In a machine for beveling sockets in saws, the combination with means for supporting the saw, of a pair of oppositely-arranged beveling-cutters, one on each side of 100 the saw, means for simultaneously driving the cutters, hand-operated and automatic means for simultaneously feeding the cutters toward each other, and clamping devices operating to hold that part of the saw upon which the cutters 105 operate, substantially as described.

10. In a machine for beveling sockets in saws, the combination with means for supporting the saw, of a pair of oppositely-arranged cutter-heads, one on each side of the 110 saw, a plurality of beveling-cutters mounted in each head, means for driving the cutter-heads, means for simultaneously feeding the cutter-heads toward each other, means for adjusting the position of the cutter-heads with 115 relation to each other, and clamping devices operating to hold that part of the saw upon which the cutters operate, substantially as described.

11. In a machine for beveling sockets in saws, the combination with means for supporting the saw, of a pair of cutter-heads, one on each side of the saw, means for driving the cutter-heads, means for simultaneously feeding the cutter-heads, means whereby the 120 feeding means may be caused to adjust the position of the cutter-heads with relation to each other, and clamping devices operating to hold that part of the saw upon which the cutters operate, substantially as described.

12. In a machine for beveling sockets in saws, the combination with means for axially

supporting the saw, of a pair of cutter-heads one on each side of the saw, means for driving the cutter-heads, a feed-shaft, operating connections between the feed-shaft and the cutter-heads, and means for shifting the position of the shaft in order to adjust the cutter-heads with relation to each other, and clamping devices operating to hold that part of the saw upon which the cutters operate, substantially as described.

13. In a machine for beveling sockets in saws, the combination with means for supporting the saw, of a pair of oppositely-arranged cutter-heads one on each side of the saw, a plurality of beveling-cutters mounted in each head, means for driving the cutter-heads, a feed-shaft, gearing between said shaft and each of the cutter-heads, automatic and hand-operated means for actuating the shaft, and clamping devices operating to hold that part of the saw upon which the cutters operate, substantially as described.

14. In a machine for beveling sockets in saws, the combination with means for supporting the saw, of a pair of cutter-heads one on each side of the saw, means for driving the cutter-heads, a feed-shaft, a longitudinally-adjustable bearing in which said shaft is mounted, gearing between said shaft and each of the cutter-heads, means for actuating the shaft, and clamping devices operating to hold that part of the saw upon which the cutters operate, substantially as described.

15. In a machine for beveling sockets in saws, the combination with means for supporting the saw, of a pair of cutter-heads one on each side of the saw, means for driving the cutter-heads, a feed-shaft, a longitudinally-adjustable bearing in which said shaft is mounted, gearing between said shaft and each of the cutter-heads, automatic and hand-operated means for actuating the shaft, and clamping devices operating to hold that part of the saw upon which the cutters operate, substantially as described.

16. In a machine for beveling sockets in saws, the combination with a saw-support, of a pair of oppositely-arranged cutter-heads, one on each side of the saw, a plurality of beveling-cutters mounted in each head, spindles on which the cutter-heads are mounted, a sleeve on each spindle, means for driving the spindles, a feed-shaft, worms on said shaft, gearing between the worms and the sleeves on the spindles, and clamping devices operating to hold that part of the saw upon which the cutters operate, substantially as described.

17. In a machine for beveling sockets in saws, the combination with a saw-support, of a pair of cutter-heads, one on each side of the saw, spindles on which the cutter-heads are mounted, a sleeve on each spindle, means for driving the spindles, a feed-shaft, a longitudinally-adjustable bearing in which said shaft is mounted, worms on said shaft, gearing be-

tween the worms and the sleeves on the spindles, and clamping devices operating to hold that part of the saw upon which the cutters operate, substantially as described.

18. In a machine for beveling sockets in saws, the combination with saw-supporting means, of a pair of cutter-heads, a plurality of cutters mounted in each head, a driving-shaft, connections from said driving-shaft to each cutter-head, and means for disconnecting the driving connections of one cutter-head in order to bring the cutters on the two heads into staggered relation, substantially as described.

19. In a machine for beveling sockets in saws, the combination with saw-supporting means, of a pair of cutter-heads, a plurality of cutters mounted in each head, a driving-shaft, connections from the driving-shaft to one cutter-head, and connections including a clutch from the driving-shaft to the other cutter-head, whereby the driving connections of one cutter-head may be interrupted in order to bring the cutters on the cutter-heads into staggered relation, substantially as described.

20. In a machine for beveling sockets in saws, the combination with an adjustable axial support for the saw, of a pair of oppositely-arranged beveling-cutters one on each side of the saw, means for driving the cutters, means for feeding the cutters toward each other, and clamping devices operating to hold that part of the saw upon which the cutters operate, substantially as described.

21. In a machine for beveling sockets in saws, the combination with an arm, of an axial support for the saw mounted on said arm and adjustable with relation thereto, a pair of oppositely-arranged beveling-cutters one on each side of the saw, means for driving the cutters, and means for feeding the cutters toward each other, substantially as described.

22. In a machine for beveling sockets in saws, the combination with means for supporting the saw, of a pair of oppositely-arranged cutter-heads, one on each side of the saw, a plurality of beveling-cutters mounted in each head, means for driving the cutter-heads, means for feeding the heads toward each other, a perforated block operating as a guide for one cutter-head, a perforated block operating as a guide for the other head, a recessed plate located between the blocks, and means for forcing the plate against one of the blocks to clamp the saw, substantially as described.

23. In a machine for beveling sockets in saws, the combination with means for supporting the saw, of a pair of cutter-heads, one on each side of the saw, a perforated block operating as a guide for one cutter-head, a perforated block operating as a guide for the other head, a plate having a recess corresponding in shape to the socket to be beveled, said plate having a bearing-rib surrounding

its recess, and means for forcing the plate against one of the blocks to clamp the saw, substantially as described.

24. In a machine for beveling sockets in saws, the combination with a block, of a plate having a recess corresponding in shape to the sockets in the saw, a bearing-rib surrounding the recess, a support between the plate and the saw, and an adjustable support between the block and the plate, substantially as described.

25. In a machine for beveling sockets in saws, the combination with a block, of a plate having a recess corresponding in shape to the sockets in the saw, a bearing-rib surrounding the recess, a support between the plate and the saw, and an adjustable support between the block and the plate, said support comprising a plurality of screws tapped into the block and bearing against the plate, substantially as described.

26. In a machine for beveling sockets in saws, the combination with an adjustable axial support for the saw, of a pair of cutter-heads one on each side of the saw, cutters in said heads, the cutters in one head being staggered with relation to the cutters in the other head, a driving-shaft, connections between said shaft and each of the cutter-heads, a feed-shaft, operating connections between said feed-shaft and the cutter-heads, a pair of blocks serving to guide and support said heads, a clamping-plate located between the blocks, and means for forcing the clamping-plate against one of the blocks, substantially as described.

27. In a machine for beveling sockets in saws, the combination with an adjustable axial support for the saw, of a pair of cutter-heads one on each side of the saw, cutters in said heads, the cutters in one head being staggered with relation to the cutters in the other head, a driving-shaft, connections between said shaft and each of the cutter-heads, a feed-shaft, automatic and hand-operated means for actuating the feed-shaft, operating connections between said feed-shaft and

the cutter-heads, a pair of blocks serving to guide and support said heads, a clamping-plate located between the blocks, and means for forcing the clamping-plate against one of the blocks, substantially as described.

28. In a machine for beveling sockets in saws, the combination with an adjustable axial support for the saw, of a pair of cutter-heads one on each side of the saw, cutters in said heads, the cutters in one head being staggered with relation to the cutters in the other head, a driving-shaft, connections between said shaft and each of the cutter-heads, a feed-shaft, a longitudinally-adjustable bearing for the feed-shaft, automatic and hand-operated means for actuating said feed-shaft, operating connections between said feed-shaft and the cutter-heads, a pair of blocks serving to guide and support said heads, a clamping-plate located between the blocks, and means for forcing the clamping-plate against one of the blocks, substantially as described.

29. In a machine for beveling sockets in saws, the combination with adjustable means for axially supporting the saw, of a pair of cutter-heads, one on each side of the saw, a driving-shaft, driving connections between one of said cutter-heads and the shaft, driving connections between the other cutter-head and the shaft, said connections including a clutch, a feed-shaft, a longitudinally-adjustable bearing for the feed-shaft, operating connections between said feed-shaft and the cutter-heads, a pair of blocks serving to guide and support said heads, a clamping-plate located between the blocks, and means for forcing the clamping-plate against one of the blocks, substantially as described.

In testimony whereof I have hereunto set my hand in the presence of two subscribing witnesses.

AMANDUS H. CRUSE.
